UNITED STATES PATENT OFFICE.

WILLIAM H. THOMAS, OF JENKINTOWN, PENNSYLVANIA.

WINDOW-SCREEN.

SPECIFICATION forming part of Letters Patent No. 416,083, dated November 26, 1889.

Application filed May 3, 1889. Serial No. 309,527. (No model.)

To all whom it may concern:

Be it known that I, WILLIAM H. THOMAS, a citizen of the United States, residing at Jenkintown, in the county of Montgomery and State of Pennsylvania, have invented certain new and useful Improvements in Window-Screens; and I do hereby declare that the following is a full, clear, and exact description of the invention.

10 My invention has relation to window-screens, and has for its object to provide simple and efficient means for securing the same in place in the window-frames and permitting of their ready removal therefrom.

15 My invention consists in the provision of a bolt secured in a suitable recess in each corner of the side of a window-screen, the casing of said bolt being L-shaped in transverse section and secured to said frame at said corners. Instead, however, of the bolt being actuated by a spring and normally projecting beyond the edge of the screen-frame and outside of its casing, as heretofore, the same, when the screen is not in use, normally rests 20 entirely within its casing and with equal facility rests at its extreme outside position. In fact, my improved bolt will rest just where it may be found desirable to place it. This result I accomplish through the use of

25 a flat spring secured at one end to the inside of the bolt-casing and at its other end resting on the side or top of the bolt, thus controlling the movements of the bolt and not in any wise assisting in its actuation. Thus, it will be

30 readily seen, the danger of damage to the bolt by bending or otherwise when the screens are not in use and the bolts project beyond the casing is perfectly avoided. When my improved bolts are once withdrawn, the flat 35 springs prevent their accidental movement into their projecting positions. In addition, the L-shaped bolt-casings serve to brace the screen-frame at the corners where the recesses are formed.

40 All the details of my invention will be more particularly described hereinafter, and will be clearly understood upon referring to the accompanying drawings, wherein—

45 Figure 1 is an elevation of a window-screen in position with my improvements applied thereto. Fig. 2 is an edge view of the same

with the window-frame in section. Figs. 3 and 4 are enlarged side elevations and plan views of my improvements. Fig. 5 is a perspective of a corner of the screen-frame, showing the recess therein. 55

A represents the screen secured to the stiles $b b' b^2 b^3$ of the screen-frame B in the usual manner, which frame slides on the tongues $c c'$, secured to the window-frame C. Instead, however, of providing said frame B with a groove in each side, there is provided but one groove c^2 in the stile b^3 , while on the other side there is provided a single longitudinal strip c^3 on the stile b' , which is flush with the 60 surface of said stile and is similar to one of the walls of the groove c^2 . In lieu of the other wall, there is provided a pair of square bolts D D, which occupy the position of said discarded wall and are placed at each end of the 65 stile b' , thus preventing any movement of the ends of the frame, and said bolts at the same time are of such thickness as to close up the space between the tongue c' and the window-sash C', thus preventing the entrance of insects to the compartment through such space. Said bolts slide in recesses e , extending longitudinally of the stiles $b b^2$ from their junction with the stile b' , which recesses do not, however, extend to the surfaces of said stiles, but 70 terminate a short distance therefrom, allowing for the formation of the shallow recesses $e^2 e^3 e^4$ parallel with the walls of recesses e , for the reception of the side, top, and end plates $f f' f^2$ of the bolt-casings F F', which 75 are secured therein by the screws $g g'$. The outer ends d of said bolts pass through correspondingly-squared openings f^3 in the end plates, which openings are very close to the edge of the side plates f , so as to bring said 80 ends close to the window-sash and at the same time contact with the tongue c' , for the purpose above suggested. The inner ends d' of said bolts are considerably wider than the outer ends d , having the longitudinal enlargements or swells d^2 thereon, near the edge of which, in an opening formed therein, are secured the shanks h of the thumb-pieces H, which thumb-pieces are so disposed as to slide 85 within longitudinal slots h^2 in the centrally-located concavities h' , formed in the top plates f' of the casings F F', and maintain the bolts 90 95 100

in the proper positions in the casings, said concavities or recesses being of such depth that the thumb-pieces H will not project beyond the surfaces of the top plates. The 5 sides of the inner ends d' of the bolts D D' opposite the swell d^2 are in a line with the edges of the ends d of the said bolts, which edges bear against the inside of the side plates f, thus bringing the outer ends of the bolts 10 close to the outer surfaces of the bolt-casings.

As shown in the drawings, when the bolt-casings are in place the walls thereof are flush with the surfaces of the screen-frame, and, owing to the shape of the bolt-casings, 15 being substantially like an elongated L with the end closed, the frame at its corners will be perfectly braced, thus conducing to an increased length of time of usefulness thereof. It will also be readily seen that the recesses for the bolts and their casings can be 20 quickly formed by the use of an ordinary chisel, thus cheapening the construction of the screen and at the same time greatly enhancing its value and utility. The insides 25 of the top plates f' have secured thereto, by a screw i or otherwise, a flat spring I, curved at its free end, so as to bear against and exert a pressure on the top surfaces of the outer ends d of the bolts D D', thus preventing their 30 accidental movement and causing said bolts to remain in any adjusted position, and insuring their remaining in contact with their tongues, and yet not interfering with the withdrawal of the same into their incased positions, where they will remain until manually 35 removed therefrom.

Besides the bolts coming close to the window-sash said bolts are slightly within the line of the face of the screen-frame. Consequently the latter will come into closer relation with the window-sash than do the bolts. 40

As hereinbefore intimated, I am aware that opening-actuated bolts have heretofore been employed with screen-frames, and that 45 screens have heretofore been secured at each end of one side in the window-frame, so that I do not wish to be understood as claiming the same, broadly; but

What I claim as my invention is--

50 1. In a screen-frame, the combination of

the bolt D, the bolt-casing F, a screen-frame with a recess in each corner of one of its sides for the reception of the bolt, a flat spring secured to the inside of the casing and pressing on the side of the bolt, and the casing secured to the screen-frame at said corner, substantially as and for the purpose set forth. 55

2. In a window-screen, the combination of the frame B, having the stiles b b², provided with the recesses e and the recesses e² e³ e⁴, 60 the bolts D and the casings F F' in said recesses, the screws g g', the flat springs I, pressing on said bolts, and the screws i, securing said springs to the insides of said casings, substantially as and for the purpose set forth. 65

3. In a window-screen, the combination of the frame B, having the stiles b b², provided with the recesses e and the recesses e² e³ e⁴, 70 the bolts D and the casings F F' in said recesses, the plate f', the depression h' in said plate, the slot h² in said depression, the thumb-pieces H, the shanks h of said thumb-pieces passing through said slots and into the ends d' of said bolts, the plates f², the openings f³ 75 in said plates for the passage of the ends d of said bolts, the plates f, the screws g g', the flat springs I, the screws i, securing said springs to the insides of the plates f', substantially as and for the purpose set forth. 80

4. In a window-screen, the combination, with the window-frame C, provided with the tongues c c', of the frame B, having the stile b³, with the groove c² therein, the stile b', with the strip c³ thereon, and the stiles b b², 85 provided with the recesses e and the recesses e² e³ e⁴, the bolts D and the casings F F' in said recesses, the screws g g', the thumb-pieces H, with their shanks passing through said casings and into said bolts, the 90 springs I, and the screws i, securing said springs inside of the casings, substantially as and for the purpose set forth.

In testimony whereof I have hereunto set my hand, at Philadelphia, Pennsylvania, this 95 22d day of April, A. D. 1889.

WILLIAM H. THOMAS.
